UNITED STATES PATENT OFFICE

99,553

DESIGN FOR A PARKING METER

Noel Marshall Seeburg, Chicago, Ill., and William N. Woodruff and James A. Shelley, Houston, Tex.

Application March 16, 1936, Serial No. 61,640

Term of patent 14 years

To all whom it may concern:

Be it known that we, Noel M. Seeburg, William N. Woodruff, and James A. Shelley, citizens of the United States, residing, respectively, at Chicago, in the county of Cook and State of Illinois, and Houston, in the county of Harris and State of Texas, and Houston, in the county of Harris and State of Texas, have invented a new, original, and ornamental Design for Parking Meters, of which the following is a specification, reference being had to the accompanying drawing, forming a part thereof.

Fig. 1 is a front perspective of a parking meter showing the new design.

Fig. 2 is a side perspective and Fig. 3 is a rear perspective of the same.

We claim:

The ornamental design for a parking meter as shown.

In testimony whereof we hereunto affix our signatures.

N. MARSHALL SEEBURG.
WILLIAM N. WOODRUFF.
JAMES A. SHELLEY.
